UNITED STATES PATENT OFFICE

142,582

DESIGN FOR AN ELECTRIC LIGHT BOWL

Albert J. D. Ohm, Buffalo, N. Y., assignor to Mar-
kel Electric Products, Inc., Buffalo, N. Y., a cor-
poration of New York

Application April 27, 1945, Serial No. 119,261
Term of patent 14 years

(Cl. D48—16)

To all whom it may concern:

Be it known that I, Albert J. D. Ohm, a citizen
of the United States, residing at Buffalo, in the
county of Erie and State of New York, have in-
vented a new, original, and ornamental Design
for Electric Light Bowls, of which the following
is a specification, reference being had to the ac-
companying drawing, forming part thereof.

Figure 1 is a perspective view from below of
an electric light bowl showing my new design.

Figure 2 is a bottom plan view of the same.
The dominant features of my design reside in
the surface ornamentation on the light bowl as
shown.

I claim:

The ornamental design for an electric light
bowl, as shown and described.

ALBERT J. D. OHM.
